UNITED STATES PATENT OFFICE.

WILLIAM D. FOSS, OF BELL, CALIFORNIA.

SASH HOLDER.

Application filed October 9, 1924. Serial No. 742,693.

To all whom it may concern:

Be it known that I, WILLIAM D. Foss, a citizen of the United States, residing at Bell, in the county of Los Angeles and State 5 of California, have invented certain new and useful Improvements in Sash Holders, of which the following is a specification, reference being had to the accompanying drawings.

10 This invention relates to window constructions, particularly to sashes, and has for its object the provision of means associated with a sash and co-operating with the window frame or casing whereby to avoid the use of 15 the well known weights.

An important and more specific object is the provision of friction devices held under spring tension and permanently carried by the sash and co-operating with the window 20 stile for the purpose of positively holding the sash at any desired adjusted position.

Another object is the provision of holding means of this character in which the spring tension is adjustable so as to enable the device to be used satisfactorily and successfully 25 in connection with window sashes of different weights, it being obvious that a large sash will require greater tension than a smaller one.

30 A further object is the provision of sash holding means of this character which will be simple and inexpensive in manufacture, easy to install, positive in action, convenient in use, efficient and durable in service, and 35 a general improvement in the art.

With the above and other objects and advantages in view, the invention consists in the details of construction to be hereinafter more fully described and claimed, and illustrated in the accompanying drawings in which:

40 Figure 1 is an elevation of a window showing a pair of sashes therein, parts of the sash rails being broken away to disclose the location of the holding means;

45 Figure 2 is a fragmentary edge elevation of one sash showing one of the holding members; and

50 Figure 3 is an enlarged longitudinal section through a fragment of the sash rail and the device.

Referring more particularly to the drawings, the letter A designates the side of a window frame or casing, and B represents a pair of sashes slidably mounted therein in 55 the usual manner. Ordinarily a window is provided with weights having cords or chains attached thereto, trained over suitable guide pulleys or rollers and connected with the sashes for counterbalancing the sash so 60 that it may be easily moved from one position to another and so that it will remain in any desired position. It frequently occurs that the sash cords or chains break whereupon the weights drop down within the window casing and become useless so that there 65 is then nothing to hold the sash. Another disadvantage in the ordinary construction is that the sashes may rattle especially during wind storms and may vibrate and make an objectionable noise especially in cities or other places where there is considerable traffic which naturally produces a jarring effect.

To overcome the above well recognized 70 disadvantages, I have designed the present invention which entirely eliminates the use of the well known weights. In carrying out the invention I equip each sash with a desired number of friction devices which co-operate with the sides of the window frame 75 or casing for holding the sashes in any desired position. Each friction device is formed as an elongated angular strip 10 of resilient metal, preferably spring steel, which strip is mounted within an elongated 80 recess 11 in the edge of the sash rail. One end of the recess is deepened at 12 for accommodation of the offset or angular end 13 of the strip and this deepened portion leads into a socket 14 containing a metallic 85 bushing 15 within which is located a coil spring 16 bearing against the offset or angular end of the strip 10.

Secured upon the angular end of the strip 90 is a suitable bracket or yoke 17, here disclosed as of U-shape, riveted, brazed, or otherwise mounted and having journaled therein on a pintle or pin 18 a roller 19 of metal, fiber, or any other desired or suitable material, which roller is designed to bear 95 against the adjacent side of the window frame or casing.

The strip 10 is held in place within this groove or recess 11 by means of screws 20 and 21, the former of which is intended to be left permanently in place and the latter 5 of which is capable of being screwed in to a greater or less extent whereby to vary the spring tension on the device. It will be observed that the recess 11 is slightly tapered so that by turning the screw 21 in, the strip 10 will be drawn into the recess 11 to a greater extent, thereby moving the roller 19 slightly into the socket 14. In other words 10 this second named screw 21 may be considered as a stop for limiting the outward movement of the strip and consequently the roller under the influence of the spring 16 and also 15 under the influence of the natural resilience of the strip itself. This feature is of great importance as such adjustment may be necessary to take care of variations in the fits of 20 sashes as it is obvious that in case of a loose fitting sash the roller would need to project outwardly beyond the sash to a greater extent than in the case of a more closely fitting 25 sash. Furthermore, this feature enables the device to be used successfully with sashes of different weights, it being obvious that the spring tension need not be as great for a light sash as for a heavy or large one.

30 In the use of the device it is evident that when the sash is raised and lowered in the customary manner and that whenever it is left at a desired point, the spring tension applied to the strip 10 and consequently the 35 roller will insure sufficient frictional resistance to maintain the sash in the desired position so that it cannot casually slip down. Furthermore, the device will act to take up any looseness between the sash and the window 40 frame or casing so that rattling or vibration from wind or any other cause will be positively eliminated.

From the foregoing description, and a 45 study of the drawings, it will be apparent that I have thus provided a simply constructed, inexpensive and easily applied means for the purpose specified which will efficiently perform all of the functions for which it is intended. Owing to the simplicity and fewness of parts, together with the ruggedness of the construction it is obvious 50 that there is practically nothing to get out of order so that the device should have a long and satisfactory life.

55 While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

60 1. The combination with a window casing 65 and a sash mounted therein, the side face of

the sash being longitudinally recessed and the sash at one end of said recess being formed with a socket, of a resilient strip disposed in the recess and extending longitudinally therewith, one end of the strip being inwardly off-set with respect to the sash and carrying a roller adapted to engage the window casing, a spring disposed in said socket and engaging the inwardly off-set end 70 of the strip and urging this end of the strip and the roller outward, the end of the strip opposite said off-set portion resting flat against the bottom of said recess and being attached to the sash frame, the recess between said point of attachment of the strip and the off-set portion thereof having its bottom re-entrantly inclined, and a screw 75 passing through the strip opposite the deepest portion of this last named part of the recess and engaging the window sash whereby the strip may be shifted inward against the action of said spring or may be permitted to shift outward under the action of the spring.

2. The combination with a window casing and a sash mounted therein, the sash being provided with a socket extending inward from the edge face of the window casing and with a recess extending longitudinally toward said socket, that portion of the recess adjacent the socket being inclined inward and intersecting the socket midway of its depth, a longitudinally extending strip mounted within the recess and extending into the socket and carrying a casing engaging roller, that portion of the strip disposed within the off-set portion of the recess being angularly bent inward and the recess for the greater portion of its length being deeper than the thickness of the strip, a coiled compression spring disposed within the socket and bearing against the end of the resilient strip and urging said end outward, fastening means at the other end of the strip, and an adjusting screw engaging the strip and window sash between the fastening means and the socket whereby the strip may be adjusted inward against the action of said coiled spring or permitted to move outward under the action of the spring.

3. The combination with a window casing and a sash mounted therein, the edge of the sash facing the window casing having an inwardly extending socket and the edge of the sash being formed with a longitudinally extending recess intersecting said socket, that portion of the recess adjacent the socket being inwardly inclined to intersect the socket midway of its depth, a metallic sleeve disposed within the socket and formed with a longitudinally extending slot, a metallic resilient strip disposed in said recess and attached to the window sash at one end and at the other end extending through the slot in the sleeve and carrying a roller, a coiled 120

compression spring disposed within said sleeve and bearing against the free end of the strip, the strip being bent inward into the inwardly extended portion of the recess and the recess between said inwardly extended portion and the point of attachment of the strip being greater in depth than the strip, and a screw passing through this portion of the strip and into the sash whereby the strip may be shifted inward against the force of said spring or permitted to move outward under the action of the spring. 10

In testimony whereof I hereunto affix my signature.

WILLIAM D. FOSS.
